UNITED STATES PATENT OFFICE

1,931,165

SUCTION CLEANING APPARATUS

Eugene F. Martinet, Cleveland, Ohio, assignor to
 The P. A. Geier Company, Cleveland, Ohio, a
 corporation of Ohio

Application January 7, 1929. Serial No. 330,783

5 Claims. (Cl. 167—3)

My invention relates to suction cleaning apparatus, and more particularly to an attachment whereby the air currents may be disinfected or made the carrier of a volatile reagent. The object of my invention is to provide a suitable attachment for impregnating the air currents of a suction cleaner, either while dust-charged or free running, with the desired volatile substance. A secondary object is the provision of an attachment of compact structure that may be rendered inactive at pleasure.

Suction cleaning apparatus not infrequently must be operated for cleaning sick-rooms and hospitals, hence a suitable disinfecting attachment of simple and cheap construction is a desirable and sanitary adjunct. Moreover, in cleaning closets, and the like, it is equally desirable to destroy any insect life, and the use of a suitable volatile reagent is indicated. At times it is desirable to use a reagent rendered effective by moderate heat, and intermittently operative heating means also are indicated for such contingencies.

Accordingly, I have devised a simple, cheap and efficient attachment adapted to be interposed between the nozzle device and the fan casing of a suction cleaner, which may be used for various more or less volatile reagents, either at normal or elevated temperatures, to impregnate the air currents when and as desired. The features of my improvement may best be explained in connection with the accompanying drawing showing a preferred embodiment of my improvement, wherein:

Figure 1 is a view in elevation of a suction cleaning device equipped with my improved impregnating attachment;

Fig. 2 is an enlarged view of the attachment proper, shown partly in section; heating means being diagrammatically indicated therein;

Fig. 3 is a top view of the attachment with the adjustable cover removed;

Fig. 4 is a front view of the attachment and cover;

Fig. 5 is a vertical section on line 5—5, Fig. 4, including the front wall of the fan casing, and

Fig. 6 is a top view of the attachment showing the air-controlling slide.

Throughout the several figures of the drawing I have employed the same characters of reference to indicate similar parts.

A standard type of portable suction cleaning apparatus is shown in Fig. 1, and includes a fan housing or suction compartment *b* in which a power driven fan of the usual type is located, a

motor casing *a* enclosing a usual motor for operating the fan, and a suction nozzle *c* forming an air inlet communicating with the suction side of the fan casing. The motor casing *a*, the fan housing *b*, and the suction nozzle *c* are all 60 mounted upon wheels *d*. A discharge conduit or duct leads from the fan housing *b* and has a usual dust bag *b'* connected thereto. No detailed description of these parts is necessary inasmuch as the apparatus is typical of numerous approved forms of suction sweepers. 65

The improved germ destroying and disinfecting attachment *e*, which provides an auxiliary air inlet on the suction side of the fan chamber for supplying an auxiliary stream of air into the 70 stream drawn through the nozzle *c*, is interposed on the suction side of the fan between the fan housing *b* and the nozzle *c*. This attachment is preferably mounted on the fan housing *b* of cleaning appliances by screws *e6*, or the attachment may be readily applied in the same manner to old machines lacking, but requiring the same. 75

The usual air inlet means, indicated above as the nozzle *c*, is preferably detachably connected to the improved attachment *e* by any suitable 80 and well known means, such as by a bayonet joint; the notched attachment portion of such a bayonet joint being shown at *c'* in Figs. 4 and 5.

The annular body of the attachment (Fig. 2), 85 is preferably die-cast and includes a laterally positioned receptacle *e'* having a perforated bottom wall *e''*, the perforations of which provide outlet passages from the receptacle *e'* communicating with the suction passage leading from 90 the sweeper nozzle to the suction compartment or fan housing *b*.

The central transverse opening *e3* of the attachment *e* forms an air duct which registers with the suction duct openings in the fan housing *b* and nozzle *c* of the suction cleaner, while two lateral openings *e4* and a bottom opening *e5* may be provided in the body of the attachment so as to reduce the weight of the same. 95

Numerous satisfactory germicides or disinfecting reagents may be placed in the receptacle *e'* which will volatilize or evaporate at normal room temperatures to impregnate the auxiliary stream of air drawn through the receptacle *e'*. For example, crystalline paradichlorobenzene, either 105 alone or mixed with oil of cedar, may be advantageously used at normal room temperatures for air-treating clothes, draperies, clothes-closets and rooms.

However, reagents requiring a small amount of 110

heat for volatilization may sometimes be used, so that electric heating elements, each comprising an insulating core *g* and a resistance winding *g'* controlled by a switch *g''*, are inserted in the openings *e4*, for heating the attachment *e* adjacent to the receptacle *e'* to volatilize the reagent contained therein.

The receptacle *e'* is preferably provided with a removable perforated sheet metal cover *f*, whose perforations provide inlet passages from the atmosphere to the receptacle (Figs. 4-6). A slide *f'* is also mounted on the attachment and is provided with perforations adapted to register with the cover perforations so as to serve as a regulating or cut off valve for the cover perforations.

When the perforations in the slide *f'* do not register with the corresponding perforations in the cover *f*, the improved attachment is inoperative and will not supply an auxiliary stream of air impregnated with the selected reagent to the suction side of the fan, but the suction cleaning apparatus will be operated in the usual manner.

25 However, if the regulating slide *f'* is shifted so that its perforations partially or entirely register with those in the cover *f* (Fig. 5), a correspondingly varying amount of air will be drawn by the suction of the sweeper through the perforations into the receptacle *e'* and in contact with the reagent contained therein so as to impregnate the air currents with the volatile products of the reagent utilized. This auxiliary stream of impregnated air passes from the receptacle *e'* through the outlet perforations formed in the perforated bottom *e''*, through the fan chamber and into the dust bag *b'* where the dust is separated from the air currents and is held in the dust bag while the air escapes through the dust bag walls.

Meanwhile, the volatile reagent reacts to render the dust laden air and the contents of the dust bag antiseptic, and the air escaping from the dust bag is still charged with the volatile products of the reagent employed so as to impregnate the surrounding atmosphere with the same and purifying the atmosphere.

The operation of treating the matter collected by the suction cleaning apparatus, or the surrounding atmosphere, is accomplished without affecting the suction cleaning function because the opening *e3* in the attachment *e* substantially registers with the adjacent openings in the fan casing and nozzle and does not impair the operation of the suction cleaner. However, if at any time it is desired to remove the attachment from the suction cleaning apparatus, the same may be readily accomplished by removing the three screws *e6* so as to release the attachment from its connection with the fan housing *b*.

Having now described the preferred embodiment of my invention, I claim as new and desire to secure by Letters Patent, the following:

1. In combination, a suction cleaner including a power driven fan, a fan housing, and a nozzle, and an attachment interposed between said fan housing and nozzle, having an air duct registering with the suction duct openings of the fan housing and nozzle and a receptacle having inlet passages and outlet passages communicating with said air duct adapted to supply an auxiliary stream of air to said air duct. 80

2. In combination, a suction cleaner including a power driven fan, a fan housing, and a nozzle communicating with the suction side of said fan, and an attachment interposed between said fan housing and nozzle, having an air duct registering with the suction duct opening of the fan housing and with the suction duct leading from said nozzle, and a receptacle having inlet passages and outlet passages communicating with said air duct adapted to supply an auxiliary stream of air to said air duct. 90

3. In combination, a suction cleaner including a power driven fan, a fan housing, and a nozzle communicating with the suction side of said fan, and an attachment interposed between said fan housing and nozzle, having an air duct registering with the suction duct opening of the fan housing and with the suction duct leading from said nozzle, a receptacle having inlet passages and outlet passages communicating with said air duct adapted to supply an auxiliary stream of air to said air duct, and means for regulating the flow of air through said receptacle to said air duct. 100

4. In combination, a suction cleaner including a power driven fan, a fan housing, and a detachable nozzle, and an attachment interposed between said fan housing and nozzle, having an air duct registering with the suction duct openings of the fan housing and nozzle, a receptacle having inlet passages and outlet passages communicating with said air duct adapted to supply an auxiliary stream of air to said air duct, and means for regulating the flow of air through said receptacle to said air duct. 115

5. In combination, a suction cleaner including a power driven fan, a fan housing, and a nozzle, and an attachment interposed between said fan housing and nozzle, having an air duct registering with the suction duct openings in the fan housing and nozzle, a receptacle having inlet passages and outlet passages communicating with said air duct adapted to supply an auxiliary stream of air to said air duct, means for regulating the flow of air through said receptacle to said air duct, and means for heating the contents of the receptacle. 125
